ASH RECEIVER

Raymond C. Nye, Los Angeles, Calif.

Application April 2, 1956, Serial No. 40,873

Term of patent 14 years

(Cl. D85—2)

FIG. 1.

FIG. 2.

FIG. 4.

FIG. 3.

FIG. 5.

Fig. 1 is a perspective view of an ash receiver, embodying my novel design, as it appears with the removable cover in inverted position;

Fig. 2 is a side elevation of the ash receiver of Fig. 1 viewed from the direction of the arrow 2 in Fig. 3;

Fig. 3 is a plan view of the ash receiver of Fig. 1;

Fig. 4 is a vertical section on line 4—4 of Fig. 3; and

Fig. 5 is a side elevation of the ash receiver with the cover in upright closed position.

I claim:

The ornamental design for an ash receiver, as shown and described.
